UNITED STATES PATENT OFFICE.

WILLIAM G. STEVENSON, OF CHICAGO, ILLINOIS.

GRINDING-MACHINE.

1,316,860.

Specification of Letters Patent. Patented Sept. 23, 1919.

Application filed October 5, 1918. Serial No 256,944.

To all whom it may concern:

Be it known that I, WILLIAM G. STEVENSON, a citizen of the United States, and a resident of Chicago, in the county of Cook and State of Illinois, have invented certain new and useful Improvements in Grinding-Machines, of which the following is a specification.

My invention relates to grinding machines and covers several improvements, one of the most important features being emptying or unloading mechanism which is particularly adaptable when the material ground is moist or wet.

15 A machine embodying the various features of my invention is shown on the accompanying drawings, in which

Figure 1 is a side elevational view, partly in section and broken away,

20 Fig. 2 is a sectional view on plane 2—2, Fig. 1, and

Fig. 3 is a plan view of the machine with the upper part removed.

A supporting structure 5, preferably of 25 concrete, provides the pit 6 which is spanned over by a supporting frame 7. This frame has the vertical central extension 8 forming a bearing housing for the vertical shaft 9. Within the housing the shaft has the bearing 30 hub 10 secured thereto and engaging with the bearing ledge 11 which is preferably surfaced with Babbitt metal 12. The upper end of the shaft extends into the upper end of the housing and the lower end is 35 keyed to the hub 13 of the circular grinding table 14. Secured to the under side of this grinding table is the gear 15 with which meshes the pinion 16 at the lower end of the shaft 17 which is journaled at 40 its lower end in the bearing frame 18 and at its upper end in the housing 19 of a suitable driving motor whose shaft 20 carries the gear pinion 21 meshing with the gear 22 on the shaft 17.

45 The grinding table 14 supports the annular grinding plate 23 and the cylindrical wall 24 held in place between the grinding plate and the peripheral flange 25 on the table. The grinding plate is engaged by the 50 grinding rollers 26 and 27, these rollers being diametrically opposite and each pivoted on a shaft 28. Each shaft is flat-sided at its ends from which extend the lugs 29 and 30 respectively, which engage in the vertical slots 31 of opposed guide plates 32 support-

ed in the housings 33 forming part of the frame 7, protecting caps 34 and 35 being provided for the respective rollers. The rollers are thus vertically shiftable as material is carried between them and the grinding plate.

Secured to the under side of the frame 7 by screws 36 is the conical frame 37, this frame being concentric with the shaft 9 and of a diameter to bring it into register with the inner edge of the grinding plate 23, and this frame forms with the cylindrical wall 24 and the plate an annular chamber or passageway C for the material which is being ground. The hub 13 has the vertical 70 passageways 38 therethrough and at one side has the outlet opening 39. A gate 40 is secured to the shaft 41 to be swung to open or close the passageway 39, the inner face of the door being arcuate to register 75 with the inner face of the frame 37 when it is closed. Below the outlet passageway 38 is supported the funnel 42 for discharging ground material to the conveyor belt 43.

A charging spout 44 for material to be 80 ground projects through the opening 45 in the frame 7, the material flowing through the opening 46 in the base of the frame and into the chamber C, the material being deposited in advance of the roller 27. Suspended from the frame 7 is a bracket 47 which supports the mixing and deflecting plate 48, this plate engaging diagonally across the outer part of the plate 23 opposite the outer end of the gate 40 so that material will be deflected by the plate inwardly toward the outlet opening 39, the turn table rotating in the direction indicated by the arrow in Fig. 3. Diametrically opposite a similar plate 49 is supported by a bracket 85 50 extending from the frame 7, this plate also extending diagonally from the outer edge of the grinding plate toward the inner part thereof. Secured to the frame 37 opposite the plate 49 is another deflector plate 100 51 which extends diagonally a distance over the grinding plate from the frame 37.

The mechanism for controlling the setting of the gate 40 is clearly shown in Figs. 1 and 2. The vertical shaft 41 to which 105 the gate is secured is journaled in the frame 39 and has secured to its upper end the arm 52. On the end of this arm is mounted the bracket 53 to which and the arm the nut 54 is trunnioned by pins 55 and 56. 110

The shaft 57 threads at its inner end through the nut and is journaled at its outer end in the bearing frame 58 which is rotatably mounted on the frame 7 by means 5 of the stem 59. The hand wheel 60 is provided for the shaft and when it is turned the shaft, by its engagement with the nut 54, will cause swing of the arm 52 and corresponding swing of the gate 40 to control 10 the outlet 39.

Describing the operation, the material to be ground is fed into the chamber C in advance of one of the rollers 27 and is carried by the grinding table below and past 15 the roller where it is ground. The grinding table rotates quite rapidly and centrifugal force will throw the material outwardly. When the material reaches the deflector plate 48 it is shifted inwardly and thereby 20 stirred up and mixed. The inwardly deflected material will strike the gate 40 when it is closed, and the outer side of this gate is curved so as to guide and deflect the material outwardly to cause further agitation 25 and mixing thereof. The material is now acted upon by the roller 26 and then reaches the plate 49 by which it is deflected inwardly, the plate 51 then shifting it outwardly. After the material has been suffi- 30 ciently ground the gate 40 is opened to the position shown in dotted lines, Fig. 3, and the material will then be deflected by the plate 48 through the outlet 39, the material falling through the passageways 38 into the funnel 42 and to the belt 43 to be conveyed away. The rate of discharge from 35 the machine can be controlled by opening the gate to any degree.

With my improved discharging arrangement 40 the grinding machine can be quickly and efficiently unloaded. It is particularly efficient when the treated material is moist or sticky, the deflector plates positively shifting and forcing the material through 45 the outlet. The location of the outlet at the inside of the grinding table is also very desirable and important as there is no pressure exerted on the closed gate and consequently no leakage past the gate. In prior 50 structures the material outlet and its closure means are in the path of the material.

and the centrifugal pressure thereon, and leakage is apt to occur.

I do not of course desire to be limited to the exact construction and arrangement 55 shown and described as changes and modifications are no doubt possible which would still come within the scope of the invention.

I claim as follows:

1. In a grinding machine, the combination of a rotatable grinding table, an outer retaining wall for said table, an inner wall stationarily supported to surround the central portion of said table, said central portion having discharge passageway there- 60 through, rollers engaging with said table between said walls, said inner wall having a gate way, a gate for controlling said gate way, deflector plates for deflecting material inwardly on said table, said gate when closed acting to deflect material away from 65 said inner wall and outwardly on said table and when open acting to deflect and guide material through said gate way and to said discharge passageway. 75

2. In a grinding machine, the combination of a rotatable grinding table, an outer retaining wall for said table, an inner wall stationarily supported to surround the central portion of said table, said central portion having a discharge passageway there- 80 through, rollers engaging with said table between said walls, said inner wall having a gate way, a gate for controlling said gate way, said gate being pivoted at one end to 85 swing horizontally, a deflector plate stationarily mounted over said grinding table for deflecting material inwardly on said table toward the free end of said gate, said gate when closed causing deflection of the mate- 90 rial away from said inner wall and outwardly on said table, said gate when open forming a continuation of said deflector plate whereby material is deflected along 95 said deflector plate and said gate through said gate way and to said discharge passageway.

In witness whereof I hereunto subscribe my name this 30th day of September, A. D. 1918.

WILLIAM G. STEVENSON.
